Primary Examiner — Bao-Yen T Nguyen*Assistant Examiner* — Loryn K. Leblanc(74) *Attorney, Agent, or Firm* — Marshall & Melhorn, LLC(57) **CLAIM**

The ornamental design for a bipod/tripod mounting plate for video/photography equipment, as shown and described.

DESCRIPTION

FIG. 1 is a top, perspective view of a bipod/tripod mounting plate for video/photography equipment showing our new design;

FIG. 2 is a bottom, perspective view thereof;

FIG. 3 is a front view thereof;

FIG. 4 is a back view thereof;

FIG. 5 is a top view thereof;

FIG. 6 is a bottom view thereof;

FIG. 7 is a first side view thereof; and,

FIG. 8 is a second side view thereof.

The broken lines in the drawings depict portions of the bipod/tripod mounting plate for video/photography equipment and form no part of the claimed design.

1 Claim, 3 Drawing Sheets(56)
